UNITED STATES PATENT OFFICE.

WILBUR S. BLANCHARD, OF SCRANTON, PENNSYLVANIA.

CLAMPING DEVICE FOR PAPER BOXES.

SPECIFICATION forming part of Letters Patent No. 555,845, dated March 3, 1896.

Application filed June 12, 1895. Serial No. 552,583. (No model.)

To all whom it may concern:

Be it known that I, WILBUR S. BLANCHARD, a citizen of the United States, residing at Scranton, in the county of Lackawanna and 5 State of Pennsylvania, have invented certain new and useful Improvements in Clamping Devices for Paper Boxes; and I do hereby declare the following to be a full, clear, and exact description of the invention, such as will 10 enable others skilled in the art to which it appertains to make and use the same.

My invention relates to a machine for securing ends in paper boxes of different sizes and clamping the parts while they are being 15 secured in position by paste or glue, and also to the product produced thereby; and it consists in certain novel constructions, combinations, and arrangements of parts, as will be hereinafter described and specifically 20 claimed.

The object of my invention is to provide a simple, cheap, and very efficient machine for producing paper boxes of that type which have their bottom and sides formed of one 25 piece and which have ends inserted in and secured between the bottom and sides, said machine accommodating itself to the side of a box along its whole length with an equal 30 pressure without in any wise injuring the same; and a further object of the invention is the production of the box above mentioned.

In the accompanying drawings, Figure 1 represents a top plan view of my improved 35 clamping device applied to a work-table or other suitable support. Fig. 2 represents a transverse section through the device. Fig. 3 represents a longitudinal section through the same, and Fig. 4 represents the pivoted adjusting-block in different lengths.

40 A in the drawings represents a suitable working table or bench. Along the rear upper edge of the table is secured a vertical strip or bead *a* and along one of its top side edges a vertical strip or bead *a'*. The strip *a* is provided with a series of adjusting-holes 45 *a²*, and another strip *a³* may be secured on top of the table or bench slightly in front of the strip *a*, in which a supporting-rail *a⁴* may be secured and against which and the strip 50 *a'* the box being formed may rest.

B represents a lever which is pivoted at its rear end in any one of the adjusting-holes *a²*

in the strip *a* according to the depth of the box which it is desired to clamp. The lever *B* is provided with a series of adjusting-holes *b*. 55

C represents an accommodating clamp-block which is pivoted to the under side of the lever *B* through one of the holes *b*, and is of a greater width than the lever, and is pivoted so as to extend beyond the inner edge 60 of the lever, and has its rear end beveled at *c*, so that when the lever is moved to the right to its full extent the beveled end of the block will come flush with and be stopped from further movement by the bead or strip *a³*. 65 By constructing the block *C* as described its rear inner edge will first strike the side of the box being pasted, and as the lever is continued to be forced inward it will accommodate itself to the side of the box along its entire 70 depth with an equal pressure without mashing the box at any point, and especially at its lower rear corner. This would not be the case if the accommodating block *C* was not provided and constructed to extend beyond 75 the inner edge of the lever *B*. The block *C* may also be provided with a plurality of holes *c'*, through any one of which the bolt or screw *b'* may be passed, so that the block can be moved in or out to suit boxes of different 80 depths. As shown in Fig. 4, the clamping-blocks will be made of different lengths for a similar purpose. By providing a large number of adjusting-holes *a²* in the strip or bead *a* different-sized boxes, say from two inches 85 to thirty inches wide and fifteen inches deep, can be made.

D represents a front clamp, which consists of a lever *d*, which is vertically pivoted to the front edge of the table or bench in any suitable manner. In the drawings I have shown a bifurcated rod or bar *d'* secured to the under side of the table and extending a short distance beyond the front edge of the same, in which the lever *d* is pivoted in a vertical 95 manner. *d²* represents a removable horizontally-sliding clamping-block which is provided with a vertical passage *d³*, through which the upper end of the lever *d* is passed. By drawing the lower end of the lever outward 100 the clamping-block *d²* will be forced inward against a forming-block *E*, placed within the sides and end of the boxes being formed, and securely clamp the same.

The block E may be provided with a suitable aperture e or a suitable handle to assist in removing it from the box when the levers B and d have been withdrawn.

- 5 The front clamping device D is not obsoletely necessary and may be dispensed with, though it is sometimes found convenient in combination with the side clamping device. The rail a^4 forms a support for the back of the 10 box while the ends are being secured in position.

The operation of the machine when the front clamp is employed is as follows: After the parts of the box have been assembled as 15 shown in the drawings, the levers B and d are operated and the parts firmly clamped until they have sufficiently adhered, when the clamping-blocks are withdrawn and the operation repeated at the other end of the box.

- 20 The box produced consists of a single piece of material bent to form the sides and bottom of the box and end pieces having three of their edges bent up to form fastening-flaps, said ends being inserted within the sides and 25 bottom of the box and secured to the same by being pasted along the flaps of the ends.

What I claim as my invention is—

1. A machine for clamping a paper box while being manufactured, which comprises 30 in its construction a horizontally-movable lever pivoted at its rear end, an approximately long accommodating block pivoted to the under side of said lever parallel therewith intermediate the fulcrum of the lever and where 35 the power is applied; said block extending beyond the inner edge of the lever along the length of the same, and which is adapted to be brought up to the side of a box and clamp the same along its entire depth with an equal 40 pressure, substantially as described.

2. In combination with a working table or support, provided with adjusting-holes, a lever pivoted at its rear end in one of said holes and also provided with adjusting-holes, and a 45 self-adjusting side clamp pivoted in one of the holes in said lever, substantially as described.

3. A device for clamping a paper box while being manufactured which comprises in its construction a horizontally-arranged lever pivoted at its rear end, a clamping-block pivoted to the lever at a suitable point on its length and extending beyond the inner edge of the lever, whereby it can be brought in contact with the side of the box along its entire depth with an equal pressure, and adjusting-holes in the lever, substantially as described. 50

4. A device for clamping a paper box while being manufactured which comprises in its construction a horizontally-pivoted lever, a 60 clamping-block having a beveled rear edge and pivoted to the lever at a suitable point and projecting beyond the inner edge of the lever, and a stop, substantially as and for the purpose described. 65

5. In a device for clamping a paper box while being manufactured, the combination with a self-adjusting side clamp, of a forming-block inserted within the box and a front clamp, substantially as described. 70

6. In combination with a work-table having a horizontal top surface and a holding-strip, a machine for clamping the side of a paper box while being manufactured, which comprises in its construction a horizontally-movable lever pivoted at its rear end and free the rest of its length, a comparatively long broad accommodating block pivoted to the under side of said lever and which extends beyond the inner edge of the same along the length of 80 the lever and which is adapted to be brought up to the side of a box and clamp the same along its entire depth at right angles to the top of the work-table with an equal pressure without injuring the same, substantially as 85 described.

In testimony whereof I hereunto affix my signature in presence of two witnesses.

WILBUR S. BLANCHARD.
